(57) CLAIM

I claim the ornamental design for a vanity table with glass top, as shown and described.

DESCRIPTION

FIG. 1 is a top, front, side perspective view of a vanity table with glass top, showing a first embodiment of my design;

FIG. 2 is a front perspective view thereof;

FIG. 3 is a rear perspective view thereof;

FIG. 4 is a top, front, side perspective view thereof, shown in an open configuration; and,

FIG. 5 is a top, front, side perspective view of a vanity table with glass top, showing a second embodiment of my new design.

1 Claim, 5 Drawing Sheets
